UNITED STATES PATENT OFFICE.

CHARLES T. BRADY, OF DETROIT, MICHIGAN.

DESIGN FOR AN ILLUMINATED HAND GLASS.

Application filed May 16, 1927. Serial No. 21,997. Term of patent 14 years.

To all whom it may concern:

Be it known that I, CHARLES T. BRADY, a citizen of the United States, residing at Detroit, in the county of Wayne and State of Michigan, have invented a new, original, and ornamental Design for an Illuminated Hand Glass, of which the following is a specification, reference being had to the accompanying drawing, forming part thereof.

Figure 1 is a plan view of an illuminated hand glass, showing my new design, and Fig. 2 is a side elevation thereof.

I claim:

The ornamental design for an illuminated hand glass, as shown.

CHARLES T. BRADY.
